DESIGN FOR A SLIPPER SOCK OR SIMILAR ARTICLE

Alex L. Wallau, New York, N. Y.

Application July 31, 1940, Serial No. 94,092

Term of patent 3½ years

To all whom it may concern:

Be it known that I, Alex L. Wallau, a citizen of the United States of America, residing in New York city, county of New York, and State of New York, have invented a new, original, and ornamental Design for a Slipper Sock or Similar Article, of which the following is a specification, reference being had to the accompanying drawing, forming part thereof. The figure on the

drawing is a perspective view of a slipper sock or similar article showing my new design.

The opposite side of the slipper sock is the same as that shown in the drawing, but without the embroidered ornamentation.

I claim:

The ornamental design for a slipper sock or similar article, as shown and described.

ALEX L. WALLAU.
